His Attorney.

UNITED STATES PATENT OFFICE.

PHILIP K. DEVERS, JR., OF LYNN, MASSACHUSETTS, ASSIGNOR TO GENERAL ELECTRIC COMPANY, A CORPORATION OF NEW YORK.

INCLOSED-ARC DEVICE.

1,310,067.

Specification of Letters Patent. Patented July 15, 1919.

Application filed March 6, 1916. Serial No. 82,378.

To all whom it may concern:

Be it known that I, PHILIP K. DEVERS, Jr., a citizen of the United States, residing at Lynn; in the county of Essex, State of Massachusetts, have invented certain new and useful Improvements in Inclosed-Arc Devices, of which the following is a specification.

The present invention relates to electric arc devices, particularly inclosed arc lamps, in which an arc is operated between electrodes of refractory material in a gas or vapor at high enough pressure to largely suppress disintegration of the electrodes. It is the object of my invention to provide improved means for facilitating the starting of the arc.

In a co-pending application, Serial No. 82,377, filed on even date herewith, I have described and claimed an arc device containing a gaseous filling and provided with a heater adjacent the electrodes for starting the arc.

My present invention comprises an inclosed arc device containing a quantity of easily vaporizable material, for example, mercury, or an amalgam, and a heater located to vaporize said material and to thermally ionize the vapor and produce ionization of the electrodes when subjected to a difference of potential by the impact of the ionized vapor upon the electrodes.

In one of its aspects my invention comprises an inclosed arc device provided with means for furnishing the vapor of an alkali metal, for example, potassium, to the arcing space between electrodes of refractory material, as, for example, tungsten, to facilitate the starting of an arc between said electrodes. These and other aspects of my invention will be more fully described in the following description taken in connection with the accompanying drawing and the novel features of my invention will be specifically pointed out in the appended claims.

The drawing shows in Figure 1 an inclosed incandescent arc lamp provided with my improved starting means and connected to a mechanism for automatically disconnecting the starting device when the arc is operating; Fig. 2 shows diagrammatically a modification in which current for the heater is furnished by a separate source; and Fig. 3 illustrates another modification

in which the arc and the heater are supplied by the same source.

Referring to Fig. 1 of the drawing, the arc device, in this instance, a lamp, comprises a container 1 containing electrodes 2, 3 of tungsten, or other suitable refractory material. The electrodes are carried by thin supports 4, 5, preferably consisting of tungsten. They are connected to leading-in conductors 6, 7 sealed into the container in the usual manner. The globe or container 1 contains a gas inert, or substantially so, with respect to the electrodes at the operating temperature, for example, argon, neon, krypton or nitrogen. The gas should be at a pressure high enough to suppress disintegration, or sputtering, of the electrodes at starting, say, a pressure at least above several millimeters of mercury, a pressure of about 254 millimeters being preferred. In a lamp the gas should have a relatively poor heat conductivity to enable the electrodes to be heated as highly as possible to give a maximum lighting efficiency, hydrogen for that reason being distinctly unsuitable. Some of the advantages of my invention 80 may be secured in a device containing no fixed gas. The bulb also contains a quantity of easily vaporizable material 8, for example, mercury, or low melting alloy, which when vaporized will supply an atmosphere 85 of vapor in which a high efficiency arc may be operated between the electrodes 2, 3. As will be later explained an amalgam of an alkali metal is in some cases to be preferred to mercury. The envelop has a constriction 90 at 9 giving the effect of two chambers. The evolution of vapor from the mercury or the like displaces the argon or other gas into the upper chamber. The effect of the constriction is to substantially increase the 95 efficiency of the lamp.

An incandescent conductor or heater 10 is located below the electrodes between which the arc is intended to be operated and dips into the vaporizable material. This 100 heater also preferably consists of tungsten and is proportioned to be raised to a temperature of about 2000° C. under the operating conditions hereinafter described. For example, the heater may consist of 0.015" 105 tungsten wire, and may be arranged about 1/16" below the electrodes. The spur or loop 11 projects into the mercury as shown by a

broken line, the lower end being about $\frac{1}{16}$ " or less from the surface of the glass envelop. The heater is connected to supply conductors 12, 12', the conductor 12' being separately sealed into the bulb and the conductor 12 being connected to the arc supply conductor 4 so as to save a fourth seal.

The main arc electrodes 2, 3 are connected respectively by conductors 13, 14 to a source of current, such, for example, as a compensator 15, which, for example, may be included in a series circuit 16, which may contain other arc devices of the character described herein. The heater 10 is connected to one terminal of the supply source through the conductor 17, a magnet winding 18, a conductor 19, a cut-out contact 20, and the conductor 21. The heater is connected to the opposite terminal of the compensator by the conductors 6 and 13.

When the switch 22 in the circuit 13 is closed the heater 10, with a current, say, of 12 amperes, becomes incandescent, vaporizing and ionizing some of the mercury or other easily vaporizable material. As the disengaged vapor comes into contact with the heater wire it becomes still further ionized and impinges on the surface of the electrodes which are themselves heated and ionized to some extent.

The current in the coil 18 causes the core 23 connected to the dash-pot 24 to be slowly lifted, the dash-pot being adjusted for a predetermined time interval long enough to permit the ionization to proceed to a point where an arc may be started, for example, four or five seconds. When the stop 25 comes into engagement with the lever 26 the cut-out 20 is tripped, opening the heater circuit and impressing on the arc electrodes 2, 3, the full potential of the coil 15 in the series circuit which, for example, may be 200 volts. As the electrodes have already been subjected to ionization influence, an arc is started immediately, and the arc current comes to an equilibrium in a few seconds at a lower voltage, for example, 15 volts in a 12 ampere circuit. The coil 27 in the arc circuit 14, 21 now being traversed by current causes its core 28 to be attracted thus maintaining the heater circuit open, even when the core 23 has returned to its starting position.

When an alkali metal as, for example, potassium, sodium, rubidium or the like is added to the mercury in an amount sufficient to form a rich amalgam, an arc can be started between the electrodes at a lower voltage and with a lower wattage consumed in the heater. For example, in a lamp such as described above, a heater current of but 8 amperes is sufficient to start an arc in about 5 seconds, at an impressed potential as low as 75 volts. When using an alkali metal the inclosing envelop should consist

of suitable alkali resisting glass which may be purchased in the market.

In Fig. 2 the electrodes 2, 3 are connected to the secondary of a transformer 29 by the conductors 30, 31, and the ionizer 10 is connected to one terminal of the secondary of a separate transformer 32 by the conductors 33, 34, containing a cut-out 20, and a lift-magnet 18, as shown in Fig. 1, and to the other terminal of the transformer secondary by a conductor 35. When the switches 22 and 36 are closed, the heater is traversed by current, as above described in connection with Fig. 1, and the armature of the magnet 18 is pulled up. Assuming the transformers 29 and 32 to be in parallel, it is necessary to break the heater circuit before the full potential of the transformer 29 is impressed upon the electrodes. Therefore, when the cut-out 20 opens the arc will start as described in connection with Fig. 1. The arc current will cause the armature of the magnet 27 to maintain the cut-out contact open.

When the heater circuit is not in parallel with the arc and does not affect the electrical characteristics of the arc circuit, but is supplied with current from an independent source of energy, then the magnet 18, together with the lever 26, may be omitted, and the magnet 27 will open the heater circuit as soon as the arc starts.

If desired the heater or ionizer may be connected to the terminals of the arc supply source as shown in Fig. 3. The conductors supplying the heater are connected in series with a double break cut-out 37. When the magnet 18 which is in series with the heater has pulled up its armature far enough to open the cut-out 37, the full open-circuit transformer potential is impressed across electrodes 2, 3 thereby starting the arc.

What I claim as new and desire to secure by Letters Patent of the United States, is:—

1. An electric arc device comprising the combination of a sealed container, electrodes of refractory material therein, a quantity of an amalgam of an alkali metal and means distinct from said electrodes for vaporizing and ionizing part of said amalgam preliminary to starting an arc between said electrodes.

2. An electric arc device comprising the combination of a sealed container, electrodes of tungsten therein, a quantity of potassium amalgam, a resistance means for vaporizing part of said amalgam and means for impressing a current upon said electrodes having a potential high enough to start an arc between said electrodes.

3. An electric arc device comprising the combination of a sealed envelop, electrodes of refractory conducting material therein, a quantity of easily vaporizable material, electrically heated means for vaporizing and

ionizing said material, and means for impressing upon said electrodes, a current having a potential substantially higher than necessary to maintain an arc between said

5 electrodes while simultaneously deenergizing the vaporizing and ionizing means used for starting.

4. An electric arc device comprising the combination of a sealed container, electrodes 10 of tungsten therein, a quantity of liquid metal, an electric heater in contact with said metal and located in part between the liquid metal and said electrodes, and current connections independent of said metal for heating said resistance preliminary to starting an arc between the tungsten electrodes.

5. An electric arc device comprising the combination of a sealed envelop, electrodes of refractory material therein, a quantity of 20 easily vaporizable metal, a heater located to vaporize at least some of said metal and to ionize the vapor to facilitate the starting of an arc between said electrodes at a moderate potential, and means for starting an arc between 25 said electrodes subsequent to the vaporization of said metal.

6. An electric arc device comprising the combination of a sealed envelop, electrodes of refractory metal therein, a quantity of 30 liquid easily vaporizable metal, and a filament adapted to be independently heated located in part above the surface of said vaporizable metal, and in part dipping into said metal.

35 7. An electric arc device comprising the combination of a sealed envelop, tungsten electrodes therein separated by a gap, a quantity of mercury and an independently incandescible conductor located in part between the mercury and said electrodes and in contact with said mercury.

8. An electric arc device comprising the combination of a sealed envelop, tungsten electrodes therein separated by a gap, a 45 quantity of mercury alloyed with an alkali metal, and an independently incandescible conductor located in part between the mercury and said electrodes in contact with said alloy.

50 9. An electric arc device comprising the combination of a sealed envelop, tungsten electrodes therein separated by a gap, a quantity of potassium amalgam, and an in-

dependently incandescible conductor located in part between the amalgam and said electrodes and in contact with said potassium amalgam.

10. An electric arc device comprising the combination of a sealed envelop, an inert gas or vapor therein, electrodes of refractory metal, such as tungsten therein separated by a gap, and separate means for furnishing a vapor of an alkali metal to the space between said electrodes preliminary to starting an arc between said electrodes.

65 11. An electric arc device comprising the combination of a sealed container, electrodes of tungsten therein separated by a short gap, a quantity of mercury in said container, a refractory conductor in close thermal relation to said mercury and said electrodes, and electrical connections therefor at least one of which is independent of said mercury and said electrodes.

70 12. An electric arc lamp comprising the combination of a sealed container, electrodes of tungsten located in said container, leading-in wires therefor sealed into said container, a filling of gas inert with respect to incandescent tungsten and having a pressure 75 high enough to materially suppress electrical disintegration of said electrodes when an arc is operating between the same, a quantity of amalgam of an alkali metal in said container located in operative position of the lamp 80 adjacent to but out of contact with said electrodes, and a refractory heater located adjacent said electrodes and dipping into said amalgam, and means for incandescing said heater independently of the passage of current between said electrodes.

85 13. An arc device comprising the combination of a sealed envelop, electrodes of refractory material therein, a quantity of easily vaporizable material, electrothermal means 90 for vaporizing and ionizing said material, an electro-responsive device for energizing said means, switching means for deenergizing said electrothermal means and impressing a potential upon said electrodes, and 95 means for timing said switching means to operate a predetermined interval after said electro-thermal device has been energized.

In witness whereof, I have hereunto set my hand this 3rd day of March, 1916.

PHILIP K. DEVERS, JR.
